UNITED STATES PATENT OFFICE.

FREDERICK L. LA ROCHE, OF OAKLAND, CALIFORNIA, ASSIGNOR TO IRA J. COE, OF OAKLAND, CALIFORNIA.

SPRING-MOTOR.

1,278,688.

Specification of Letters Patent. Patented Sept. 10, 1918.

Application filed December 27, 1916. Serial No. 139,166.

To all whom it may concern:

Be it known that I, FREDERICK L. LA ROCHE, a citizen of the United States, residing at Oakland, in the county of Alameda 5 and State of California, have invented new and useful Improvements in Spring-Motors, of which the following is a specification.

This invention relates to a spring motor, particularly adapted for use in connection 10 with talking machines, although it will be obvious that the invention is applicable to music boxes and the like, wherever a spring motor is desired.

The primary object of the present invention is to provide a simple, practical spring actuated motor for talking machines which will be of maximum power and of minimum dimensions. This object I accomplish by employing a plurality of springs which are 20 adapted and arranged to apply all their power simultaneously to the part to be driven as distinguished from the use of a plurality of springs operating successively or in series. The present arrangement takes 25 advantage of the combined driving force of the several springs. Another object of the invention is to provide a single driving shaft, to which power is transmitted from all the spring barrels in unison, and from 30 which power is in turn transmitted, through a step-up gear train, to a governor-regulated driven shaft, as will hereinafter be more fully described. Further objects will hereinafter appear.

35 The invention consists of the parts and the construction and combination of parts as hereinafter more fully described and claimed, having reference to the accompanying drawings, in which—

40 Figure 1 is a plan section, partly broken away, on line 1—1 of Fig. 2.

Fig. 2 is a side elevation of the spring motor.

Fig. 3 is a detail view of the pawl and 45 ratchet by which the winding shaft is locked.

Referring to the drawings in detail, A indicates the turntable of a talking machine and 2 the main frame of same; and 50 suitably secured to the lower side of said frame is a spring motor generally indicated at B. This motor consists of an upper and a lower plate, such as indicated at 4 and 5, which are spaced apart and secured together 55 by means of four stud bolts 6 which are positioned, one at each corner of the plates.

Journaled intermediate the plates is a pair of shafts 7 and 8, and turnably mounted on each shaft is a barrel 9, interiorly of which is mounted a spring 10. Secured on 60 each barrel is a spur gear 11, and secured on each shaft 7 and 8 is a spiral gear 12. Mounted below the upper plate 4 and supported in journals 13 is a winding shaft 14, and secured on said shaft is a pair of spiral 65 pinions 15 which intermesh with the spiral gears 12. Secured on the outer end of the winding shaft 14 is a crank 16 and secured on the shaft, adjacent to the winding crank, is a ratchet gear 17 which is locked against 70 movement in one direction by means of a weighted pawl 18.

The springs 10, mounted within the barrels 9, are secured at their inner ends, as at 75 19, to the shafts 7 and 8 which they surround and at their outer ends, as at 20, to the barrels 9. The connections thus formed permit the tension of the springs to turn the barrels, together with the gears 11, in the direction of arrows a, while the shafts 80 7 and 8 are remaining stationary, said shafts being locked against movement except when the springs are rewound by means of the pawl and ratchet secured upon the winding shaft 14.

85 Journaled between the upper and lower plates 4 and 5 are three alined shafts 21, 22 and 23. The shaft 21 will hereinafter be termed the driving shaft, shaft 22 the intermediate shaft and shaft 23 the driven shaft. 90 Secured upon the shaft 21 is a spur pinion 24 and a large spur gear 25. The pinion 24 intermeshes with both of the gears 11, while gear 25 intermeshes with a pinion 26 secured upon the intermediate shaft 22. Driving movement transmitted to the intermediate shaft, through the gears 25 and 26, is in 95 turn transmitted through an intermediate gear 27 which meshes with a pinion 28 secured upon the driven shaft. The step-up gear train thus provided permits the comparatively slow unwinding movement of the barrels 9 to turn the shaft 23 at a high speed which is automatically controlled by means of a governor, generally indicated at C. 100

105 This governor consists of a shaft 29 carried by journals 30. Secured on said shaft, near one end, is a collar 31 which is connected with a sliding collar 32 by means of a pair of weighted spring arms 33. Secured 110 upon the sliding collar 32 is a friction disk 34 and pivotally mounted in journals 35,

secured upon the lower plate, is a shaft 36, upon which is mounted a U-shaped rocker arm 37 which carries a pair of friction shoes 38. The shaft 36 is surrounded by a coil 5 spring 39 which normally tends to swing the U-shaped arm, carrying the shoes 38 into engagement with a friction disk, but this rocking movement is regulated and adjusted by means of a screw 39^a, which engages an angle 10 arm extension 40 formed on the shaft 36.

The governor proper is driven directly from the shaft 23 by the gears 41 and 42 and revolving movement thus transmitted creates a sufficient centrifugal action to cause the 15 weighted spring arms to expand and pull the friction disk into engagement with the shoes 38. The speed of the motor is in this manner easily regulated as the position of the shoes 38 may be adjusted by the screws 39, 20 as previously described.

A spring motor constructed as here shown is not only simple, compact and substantial in construction but occupies less space than the general type of motors now employed; 25 this comparatively flat and compact construction being permitted by the arrangement of the spring barrels 9 and the connected transmission gears. The winding of the motor can practically be done by anyone 30 as the gear ratio between the gears 12 and 15, together with the length of the crank arm 16, is such that comparatively little strength is required to perform the winding operation.

35 The weighted pawl 18 automatically locks the winding shaft the moment the crank 16 is released and simultaneously locks the parallel shafts 7 and 8 against turning movement. The barrels 9 are, therefore, free to 40 unwind as long as there is sufficient tension in the springs 10, whether the motor is being rewound or not. A continuous uninterrupted operation of the motor is, therefore, possible; the speed being at all times automatically regulated by the governor C.

The turntable A may be secured upon any 50 of the shafts 21, 22 or 23 shown, but, preferably, upon shaft 23 which is extended and provided with an arbor 50 for the reception 55 of the turntable described. While the motor is here described and employed in connection with a talking machine, it is obvious that its application may be extended for many other purposes; for instance, as a driving motor of a clock, music box, or any other machine, and while two spring barrels are here shown, it is obvious that any suitable number may be employed and also that the materials and finish of the several 60 parts of the mechanism may be such as the experience and judgment of the manufacturer may dictate.

The arrangement of two or more spring

barrels which are adapted to be wound in unison considerably reduces the time consumed in rewinding, and the gear train arrangement which permits two or more barrels to transmit their power in unison permits a greater output of power and also a more constant torque during the unwinding 65 70 operation.

I wish it understood that various changes in the form, proportions and minor details of construction may be resorted to within the scope of the appended claims, and that I do 75 not wish to limit myself to the specific design and construction here shown.

Having thus described my invention, what I claim and desire to secure by Letters Patent is—

80 1. A spring motor comprising a frame, a pair of vertically disposed shafts journaled in the frame, a barrel turnably mounted on each shaft, a spring carried by each barrel having its inner end secured to the shaft and its outer end to the barrel, a winding gear secured on each barrel, a horizontally disposed winding shaft journaled in the frame, a pair of pinions secured on said shaft, one intermeshing with each winding gear, a 85 driving shaft vertically positioned and journaled in the frame, a driving pinion secured on said shaft, a pair of driving gears secured one on each barrel intermeshing with the driving pinion, means for turning the wind- 90 driving shaft, and means for automatically regulating the speed of the driving shaft.

95 2. A spring motor comprising a frame, a pair of vertically disposed shafts journaled in the frame, a barrel turnably mounted on each shaft, a spring carried by each barrel having its inner end secured to the shaft and its outer end to the barrel, a winding gear secured on each barrel, a horizontally disposed winding shaft journaled in the frame, 100 a pair of pinions secured on said shaft, one intermeshing with each winding gear, a driving shaft vertically positioned and journaled in the frame, a driving pinion secured on said shaft, a pair of driving gears secured 105 one on each barrel intermeshing with the driving pinion, means for turning the winding shaft, means for automatically regulating the speed of the driving shaft, and means 110 for locking the winding shaft against rotation in one direction, said means comprising a ratchet wheel secured on the winding shaft and a pawl engageable with the ratchet wheel.

115 In testimony whereof I have hereunto set 120 my hand in the presence of two subscribing witnesses.
